BUTTONHOLE SEWING MACHINE

Edward B. Allen, deceased, late of Newtown, Conn., by Josephine W. Allen, administratrix, Newtown, Conn., and Maurice D. Knox, Devon, and Harold C. Faulkner, Long Hill, Conn., assignors to The Singer Manufacturing Company, Elizabeth, N. J., a corporation of New Jersey

Application November 10, 1936, Serial No. 110,026

15 Claims. (Cl. 112—71)

This invention relates to sewing machines, more particularly of the buttonhole type, and has for an object to provide an automatic lock-stitch eyelet-end buttonhole sewing machine which will 5 sew a lock-stitch buttonhole having radially disposed stitches at one end, which may be an eyelet-end, and a bar at the other end. Such a buttonhole is particularly adapted for use in white goods, such as collars and cuffs, as the eyelet-end 10 provides clearance for the shank of the usual collar or cuff button. A further object of the invention is to provide a machine which may be readily converted to sew lock-stitch eyelet-end square-barred buttonholes of various lengths within the 15 capacity of the machine. A still further object of the invention is to provide means to vary the number of barring stitches at the barred end of the buttonhole.

With the above and other objects in view, as will hereinafter appear, the invention comprises 20 the devices, combinations and arrangements of parts hereinafter set forth and illustrated in the accompanying drawings of a preferred embodiment of the invention, from which the several 25 features of the invention and the advantages attained thereby will be readily understood by those skilled in the art.

In the accompanying drawings Fig. 1 is a right 30 side elevation of a buttonhole sewing machine, embodying the invention. Fig. 2 is a top plan view of a lock-stitch pyramid-purl eyelet-end, square-barred buttonhole produced by the machine of Fig. 1. Fig. 3 is a left side elevation of the machine. Fig. 4 is an enlarged view of the 35 bar-stitch counting mechanism of the machine. Fig. 5 is a front end elevation of the machine. Fig. 6 is a rear end elevation of the machine. Fig. 7 is a bottom plan view of the machine. Fig. 7a is a detail bottom plan view of the rapid-feed 40 clutch-operating arm shown in Fig. 7. Fig. 8 is a horizontal sectional view through the bracket-arm standard of the machine, showing the bed in plan. Fig. 9 is a horizontal sectional view through the bar-stitch counting mechanism. Fig. 9a is a face view of an element of Fig. 9.

Fig. 10 is a transverse vertical section through the machine bed substantially on the line 10—10, 45 Fig. 7. Fig. 10a is a reverse view of a latch element of Fig. 10. Fig. 11 is a similar section substantially on the line 11—11, Fig. 7. Fig. 12 is an axial section through the feed throw-out clutch shown in Figs. 7 and 11. Fig. 13 is a bottom face view of the clutch shown in Fig. 12. Fig. 14 is a section on the line 14—14, Fig. 11. Fig. 15 is a section on the line 15—15, Fig. 11. Fig. 16 is an

axial section through the feed throw-out clutch-driving shaft. Fig. 17 is a vertical section taken longitudinally of the machine bed through the shuttle mechanism mounted therein. Fig. 18 is an elevation of the parts shown in Fig. 17 looking 5 from the right. Fig. 19 is a vertical section through the shuttle-carrying turret looking at the face of the shuttle.

Fig. 20 is a section on the line 20—20, Fig. 17. Fig. 21 is a section on the line 21—21, Fig. 19. Fig. 22 is a section on the line 22—22, Fig. 19. Fig. 23 is a top plan view of the overhanging bracket-arm of the machine. Fig. 24 is a perspective view of the shuttle-driver. Fig. 25 is a perspective view of the shuttle-body. Fig. 26 is a side elevation of the needle-vibrating mechanism. Fig. 27 is a section on the line 27—27, Fig. 26. Fig. 28 is a vertical section on the line 28—28, Fig. 26. Fig. 29 is a section on the line 29—29, Fig. 28.

Fig. 30 is an elevation of the lower end of the needle-bar showing the yoke and needle-clamp-block. Fig. 31 is a perspective view of the rotary needle-bar-bushing. Fig. 32 is a perspective view of the laterally reciprocating guide-block for the needle-clamp-block. Fig. 33 is a vertical section on the line 33—33, Fig. 23. Fig. 34 is a section on the line 34—34, Fig. 33. Fig. 35 is a perspective view of an element of Figs. 33 and 34. Fig. 36 is an inner face view of the readily removable and replaceable pattern wheel, together with associated parts of the rapid-feed throw-out mechanism controlled thereby. Fig. 37 is a top plan view of the removable pattern-cam and the lever which is actuated thereby to stop the feed of the work-clamp and initiate the square-bar-stitching operation at the end of the buttonhole. Fig. 38 is a side elevation of the buttonhole cutter levers and their actuating cams. Fig. 39 is a transverse vertical section through the work-supporting plates of the work-clamp, showing the buttonhole cutter levers in front end elevation. Fig. 39a is a detail sectional view of an element of Fig. 39. Fig. 40 is a fragmentary view of the portion of the bed-casting which carries the turret supporting bearing, and Fig. 41 is a section on the line 41—41, Fig. 17.

The machine frame comprises the hollow box-like bed 1 from one end of which rises the standard 2 of the overhanging bracket-arm 3 terminating in the head 4.

Journaled within and lengthwise of the bed 1, is the main sewing shaft 5, Fig. 1, which, through the one-to-one bevel gears 6, 7, drives the vertical shaft 8 journaled within the standard 55

2. The shaft 8 has a one-to-two speed-multiplying bevel-gear driving connection 9 with the upper or needle-bar-reciprocating shaft 10 which is journaled within and lengthwise of the bracket-arm 3 and has the usual crank 11 and link-connection 12 with the vertically reciprocatory hollow needle-bar 13 mounted in the head 4.

The hollow needle-bar 13, Figs. 28 and 30, has fixed to its lower end the yoke 14 carrying the cross-pin 15 on which is slidably mounted the needle-clamp-block 16 having at its upper end a guideway 17, Fig. 28, embracing the horizontal member of the yoke 14. The block 16 carries the eye-pointed needle 18. The yoke 14 is slidably received at one end in the guideway 19, Figs. 29 and 31, in a vertical arm 20 depending from a block 21 fixed to the lower end of the needle-bar-bearing bushing 22 journaled in the head 4 and having the pinion 23 fixed to its upper end, whereby turning movements may be imparted to it, as hereinafter explained, as in stitching around the eyelet-end of a buttonhole.

The block 21 also has depending from it another arm 24 which is spaced from the arm 20. The arms 24 and 20 carry a cross-pin 25 on which is horizontally slidably mounted a vertical guide arm 26 having a guideway 27 receiving the spaced rearward extensions 28 of the needle-clamp-block 16. The guide-block 26 is steadied on the cross-pin 25 by having its upwardly extending end 26' slidably received in a guideway 26'', Fig. 28, in the block 21; said guideway being completed by the cover-plate 26^a. The needle 18 is thus supported for endwise reciprocatory and laterally vibratory movements in a rotary support which is turnable about a vertical axis.

The vertical guide-block 26, which imparts the lateral vibratory movements to the needle-clamp-block 16, is connected by a link 29, Fig. 26, of adjustable length to an arm 30' fixed to one end of a rock-shaft 30 journaled in the block 21 and having fixed to its other end an arm 31, Fig. 27, which pivotally carries a guide-block 32 received in the circular groove 33 in the ring member 34 fixed to the lower end of the vertical slide-rod 35, Fig. 5, journaled in the head 4. The ring 34 is steadied by the fixed guide-pin 36 which it slidably engages. Thus, vertical movements of the slide-rod 35 and ring 34, impart lateral vibratory movements to the needle 18 in any position of the plane of vibration of the latter.

The rod 35 is reciprocated vertically, to impart lateral vibratory movements to the needle 18, by the following mechanism. Clamped to the rod 35 is a block 37, Fig. 5, which extends laterally through a slot 38 in one side wall of the head 4 and has pivotally connected thereto one end of a link 39 the other end of which is adjustably and pivotally secured in the slotted segmental arm 40 of a bell-crank lever 40, 41 fulcrumed at 42 on the head 4. The arm 41 of the bell-crank lever is connected by the link 43 to the crank-pin 44 projecting from the outer face of a crank-head 45 pivoted at 46, Fig. 34, on the disk-shaped head 47, Fig. 33, at one end of the hollow shaft 48 journaled within and transversely of the bracket-arm standard 2. Movement of the crank-head 45 about the pivot-screw 46 changes the eccentricity or operative radius of the crank 44 relative to the axis of its drive-shaft 48.

This adjustable crank mechanism is built substantially in accordance with the disclosure in the Allen et al. application, Serial No. 759,200; filed Dec. 26, 1934. The crank-head 45 has set 75 into its inner face two spaced plates 49, 49, Fig.

33, providing an inclined guideway 50 which receives the inclined head 51 of the push-rod 52 extending through the hollow shaft 48 and biased in one direction by the spring 53 to carry the stop-lug 54 into engagement with the adjustable stop 55, Fig. 1, mounted on the disk-shaped head 47. The stop 55 determines the position of minimum throw of the crank 44 and it is set for the desired amplitude of needle-vibration in sewing around the buttonhole exclusive of the square-bar end stitches 56, Fig. 2. At the end of the return side-stitching operation on the buttonhole the amplitude of needle-vibration is increased to sew the square-bar stitches 56 and this is done by mechanism to be hereinafter described which operates the lever 57, Figs. 3, 5 and 6, fulcrumed at 58 on the machine frame and carrying at its upper end an endwise adjustable tappet-screw 59, Fig. 33, adapted to push against the free end of the push-rod 52. The means for imparting intermittent semi-rotational impulses to the crank-shaft 48 will be hereinafter described.

Detachably mounted on the transverse frame member 60, within the bed 1, is the turret carrier block 61 having the upper and lower spaced bearings 62, 63 for the tubular stem 64 of the turret 65 carrying the yieldingly separable shuttle race rings 66, 67, Fig. 21, in which is journaled the conventional sewing machine shuttle 68 carrying the usual bobbin 69, Fig. 17, of under thread. The shuttle 68 is oscillated in its raceway by means of a shuttle driver 70 of usual form which is carried by the shaft 71 journaled in the bearing 72 at the rear of the turret 65. The shaft 71 has pinned to it a pinion 73 meshing with the sector gear 74 fixed to one of the trunnions 75, Fig. 22, of the rocking sleeve 76 journaled in the turret 65. The sleeve 76 is entered by the pin 77 the bifurcated head 78 of which is pivoted at 79 to the upper end of the reciprocatory rod 80 slidable in the turret stem 64.

Screwed to the longitudinally ribbed face 81, Figs. 17, 20 and 41, of the rod 80 are two spaced gibs 82 which extend outwardly through the slot 83 in the tubular stem 64 of the turret and embrace the ring member 84 which surrounds the stem 64. The ring member 84 is carried by the slide-plate 85 guided in the vertical guideway 86 in the turret-carrier block 61. The slide-plate 85 has a stud-pin 87 projecting rearwardly therefrom and this stud-pin is connected by the pitman 88 to the crank 89 on the shaft 90 journaled in the carrier 91 which, in turn, is journaled on the bearing bushing 92 in which the main sewing shaft 5 is journaled. The bushing 92 is set into an aperture 93 in the frame member 60. The shaft 90 has fixed to it a pinion 94 driven by the gear 95 of double its size on the main shaft 5.

In order to compensate the shuttle mechanism 60 for the different lateral positions of the needle, provision is made to accelerate and retard the shuttle driving shaft 90 so that the shuttle beak will be properly timed relative to the needle in the different lateral positions of the needle. To this end there is mounted on the main sewing shaft 5 an eccentric 96 embraced by the eccentric-fol-lower lever 97 the forked lower end of which slidably embraces the anchor-block 98 fixed to the rockable pin 99 journaled in the frame block 100, Fig. 40, screwed to the frame cross-member 60. The upper forked end of the lever 97 embraces the block 101 rotatively free on the shaft 90 and confined between the collar 102, Fig. 17, and the head of the screw 103. Thus, rotation of the 75

main shaft 5 imparts oscillatory movement to the carrier 91 for the crank-shaft 90 which latter is given two rotations for one complete to-and-fro oscillation of the carrier 91. The amount of compensation is chosen to be intermediate the exact compensations required for the needle in sewing the side stitches of the buttonhole and the barring stitches across the end of the buttonhole. In other words, the shuttle is slightly over-compensated when sewing the side stitches and eyelet-end of the buttonhole and is slightly under-compensated when sewing the longer barring stitches across the end of the buttonhole. This average compensation is found to be quite satisfactory and avoids the necessity of complicating the mechanism to secure exact compensation for all amplitudes of needle-vibration.

The shuttle thread is delivered through the apertured end of the thread-case arm 104, Fig. 19, in which the usual bobbin 69 is housed; the arm 104 being freely received in the notch 105 in the plate 106 screwed to the outer shuttle race ring 67 which is pressed by the springs 107 against the inner shuttle race ring 66. The thread-case 25 108 is thus restrained from oscillating with the shuttle 68. There is mounted on the vertical back-plate 109 of the shuttle race, Fig. 18, the shank 110 of the button-like needle-throat member 111 formed with the needle-receiving slot 112. The needle-throat member or button 111 rises through the work-exposing slot 113, Figs. 8 and 39, in the lower clamp-plates 114 and supports the work against the thrusts of the needle 18.

35 The turret 65 and needle-bar-rotating bushing 22 are coaxially mounted and are turned in unison by the usual means, to position the stitches radially around one end, for example, the eyelet-end of the buttonhole. The turret pinion 115 is engaged by the sector gear 116, Fig. 7, which is fixed to the lower end of the rock-shaft 117, Fig. 18, journaled in the bearing block 118 screwed to the frame cross-member 60. Secured to the upper end of the rock-shaft 117 is the arm 119 which is connected by the link 120 to the arm 121, Fig. 7, of a lever 122 fixed to the lower end of the upright shaft 123 and having a follower 124 entering the radial stitch-positioning cam-groove 125 in the feed-wheel 126 mounted within the bed 1. The upright shaft 123 carries an arm 127, Fig. 23, at its upper end, which arm is connected by the link 128 to the sector gear 129 meshing with the pinion 23 of the needle-bar-turning carrier-bushing 22.

55 The work-clamp is of the usual construction disclosed in the Allen Reissue Patent No. 15,324. The lower clamp-plates 114 which carry the upper clamp-feet 130 are mounted on the cross-slide plate 131, Fig. 7 which slides laterally of the machine bed on the cross-rod 132 of the longitudinal slide-frame 133. The longitudinal slide frame of the present machine preferably carries the slide-rod 134 which is guided in the bed lugs 135, 136, Fig. 3.

65 Travelling movements lengthwise of the bed 1 are imparted to the longitudinal slide frame 133 by means of the longitudinal feed cam-groove 137 in the feed-wheel 126. The cam groove 137 is entered by the follower roll 138 on the lever 139 fulcrumed at 140 on the bed 1 and connected by the link 141 to the longitudinal slide frame 133. The travelling movement of the longitudinal slide frame 133 is sufficient, not only, to space the stitches lengthwise of the buttonhole, but also 70 to carry the work-clamp to and fro between

stitching position and buttonhole cutting position where the buttonhole cutters may operate on the work without interfering with the stitch-forming instrumentalities.

The work-clamp receives its lateral movements 5 as follows:—Secured to the cross-slide plate 131 is an extension-plate 142 the head 143 of which is formed with a groove 144 extending lengthwise of the bed 1. This groove 144 is entered by the block 145 on the pin 146 mounted at the front 10 end of the lever 147 fulcrumed at 148 on the frame lug 149. The lever 147 carries at its rearward end the vertical spring depressed slide-bolt 150 which in its lower position enters the lateral feed cam groove 151 in the control or pattern wheel 15 152 which is removably mounted on the cross-shaft 153 journaled in the bed 1. The cross-shaft 153 carries a bevel-gear 154 which meshes with the bevel gear 155 fast to the feed-wheel 126. The feed-wheel 126 and removable control or 20 pattern wheel 152 are thus geared together in one-to-one driving relation to rotate in unison, each making one complete rotation per buttonhole-producing cycle.

The wavy portion of the cam track 151 shown 25 in Fig. 7 is the portion which controls the side-shift movements of the work-clamp in sewing around the eyelet-end of a buttonhole. The camtrack 151 has a widened portion 156, Fig. 5, 30 which permits the follower lever 147 to be suddenly shifted to centralize the work-clamp at the end of the second side-stitching operation on the buttonhole for the square-bar stitching operation. The means for so shifting the lever 147 comprises a block 157, Figs. 36 and 37, having 35 a doubly beveled nose 158 and a plate-like shank 159 which is secured to the pattern cam 152.

When the second side-stitching operation is completed the beveled nose 158 of the block 157 engages the lever 147, Fig. 37, and suddenly 40 shifts it to the left or in a direction to centralize the work-clamp relative to the field of lateral vibration of the needle; this motion of the lever 147 being permitted by the widened portion 156 of the cam-groove 151 and yieldingly 45 resisted by the biasing spring 160, Fig. 3. At this same time the other side of the nose 158, Fig. 37, engages and swings the lever 161 which is fulcrumed at 162 on the bed 1 and which engages and shifts the lever 57 to increase the amplitude of vibration of the needle for the bar-stitching operation. 50

The main sewing shaft 5 is controlled as to its period of operation by means of a stop-motion device of the usual construction disclosed in said 55 Allen reissued patent. Such a stop-motion device comprises the stop-lever 163 fixed to the rock-shaft 164 and carrying the vertically slideable stop-tooth 165 which engages the notched stop-cam 166 associated with suitable clutch- 60 mechanism (not shown) within the continuously running belt-pulley 167. When the stop-motion lever 163 is in its full-line position, Fig. 3, the main sewing shaft 5 and the stitch-forming mechanism driven thereby are at rest. When 65 the stop-motion lever 163 is shifted to its dotted line or running position, the stitch-forming mechanism is started. To shift the stop-motion to running position the rock-shaft 164 has fixed to it a depending crank-arm 168 which is connected by a link 169, such as disclosed in the Allen Patent No. 1,504,306, of Aug. 12, 1924, to a lever 170 fulcrumed at 171 on the bed 1 and having a follower nose 172 in position to be engaged by the cam incline 173 on the pattern 70 75

- wheel 152. When the stop-motion lever 163 is shifted to running position by the cam incline 173, it is retained in such position by the engagement of the nose of the spring energized bell-crank latch-lever 174 with the notch 175 in the link 169. At the end of the sewing operation the spring latch 174 is tripped to stop the stitch-forming mechanism by the bar-stitch counting mechanism to be hereinafter described.
- 10 During the sewing of the sides and eyelet-end of the buttonhole, the connected feed-wheel 126 and pattern-wheel 152 incorporating the longitudinal feed-cam 137, the lateral feed-cam 151 and the radial stitch-positioning cam 125 are given a step-by-step rotary motion by mechanism driven by the main sewing shaft, as follows:—The bevel gear 7 at the lower end of the upright shaft 8 is provided at its under face with two diametrically opposed pins 176, Figs. 11, 12, 14, 15 and 16, which impart step-by-step rotary motion to the star-wheel 177 fixed to the upper end of the sleeve-shaft 178 journaled in the frame spider 179. The sleeve-shaft 178 has fixed to its lower end, Fig. 12, the external or live ring-element 180 of a roll-type friction clutch of known construction. The live clutch element 180 has formed integral with it a gear 180' which meshes with the pinion 181, Fig. 11, fixed to the lower end of the shaft 182 to the upper end 30 of which, Fig. 33, is fixed the bevel gear 183 meshing with the bevel pinion 184 of half its size fixed to the sleeve shaft 48 which imparts lateral vibratory movements to the needle.
- Disposed within the live clutch-element 180, Fig. 13, are the usual spring-pressed cylindrical clutch rolls 185 disposed in the clutch-pockets 186 of the driven element or clutch-spider 187 fixed to the driven shaft 188 which is journaled within the sleeve-shaft 178. The clutch rolls are shifted to de-clutching position by the levers 189 the tails 190 of which are expanded by the cone 191 which is slidable vertically on the lower end of the shaft 188 and has a peripheral groove 192 entered by the roller stud 193, Figs. 7, 10 and 11, 40 on the stitching feed-clutch operating lever 194 fulcrumed on the stud 195 carried by the frame lug 196. The clutch-operating lever 194, Fig. 10, extends outwardly through a slot 197 in the machine bed, and is biased upwardly to de-clutching position by the spring 198. The lever 194 is retained in its lower or clutching position by means of a spring-pressed latch-lever 199 fulcrumed at 200 and having a notch 201 in its lower end which is engaged by a lateral tooth 202 on a plate 203 screwed to the lever 194. When the latch-lever 199 is tripped, the clutch-lever 194 is released and is drawn upwardly by its spring 198 to de-clutch the shaft 188 from the pin and star-wheel drive mechanism which is driven by the main sewing shaft 5.
- 50 The shaft 188 which is under control of the stitching-feed clutch, is connected to drive the feed-wheel mechanism, as follows:—The shaft 188 has fixed to its upper end a pinion 204 meshing with a gear 205 fixed to a short shaft 206 having a pinion 207 at its upper end. The pinion 207 is connected by the gear 208, Fig. 7, to the feed-wheel gear 209.
- As the purpose of the clutch-mechanism above described is to disconnect the feed and pattern wheels from the sewing shaft 5 during the square-bar stitching operation across the finishing end of the buttonhole, the de-clutching latch lever 199 is arranged to be tripped by the swinging motion of the levers 57 and 161, Fig. 37, derived

from the bevel-nosed block 157 on the pattern wheel. It will be understood that simultaneously with the shifting of the work-clamp to its central position, the feed and pattern wheels are disconnected from their driving means and stand still, while the needle, with increased amplitude of lateral vibration, sews the final or barring stitches.

The number of barring stitches is controlled by a bar-stitch counting mechanism, as follows:— 10 Fixed to the side of the machine bed is a stud-pin 210, Fig. 9, which has freely mounted thereon the lever 211 and the peripherally toothed sector 212 the latter having a recess housing a biasing spring 213 which tends to turn the sector 212 in a counterclockwise direction, Fig. 4, and initially retains the shoulder 212' on the sector 212 in engagement with the stop-arm 214 carried by the lever 215 fulcrumed for adjustment on the pin 210. The lever 215 is adjustable about its fulcrum and is retained in adjusted position by the screw 216 which passes through the arcuate slot 217 in the lever. A pointer 218, Fig. 3, on the lever plays over a scale which may be graduated to indicate the number of barring 25 stitches to be made. The actuating lever 211, Figs. 9 and 9a carries a pivot-screw 219 on which is mounted the pawl 220 adapted to engage the teeth of the sector 212. The pawl 220 has a tail 221 which is biased by the spring 222 in a direction to press the pawl 220 against the toothed sector 212. The actuating lever 211 has a ball-stud 223 which is embraced by the lower end of a link 224 the slotted upper end of which is entered by the screw-stud 225 on the free outer 35 end of the rapid-feed clutch-operator push-bar 226, Fig. 11, the inner end of which is pivoted at 227 to the upstanding arm 228 of a bell-crank lever, the forked arm 229 of which embraces the crank 230 on the rapid-feed shaft 231 which is 40 continuously driven by the usual gear-connections 232, Fig. 6, with the gear 233 fast to the belt-pulley 167. The push-bar 226 thus receives constant endwise reciprocatory motion and is biased upwardly by the spring 226' into sliding 45 engagement with the overhanging latch 234, Fig. 36, which is fulcrumed at 235 on the bed 1. The endwise reciprocations of the push-bar 226, Fig. 11, while engaged by the latch 234, imparts through the link 224 an oscillatory movement to the lever 211 of the bar-stitch-counting mechanism. The amplitude of this oscillatory movement is a little greater than the angular spacing of the teeth of the sector 212 so that when the pawl 220 engages the sector 212 the latter will 50 be advanced by the pawl 220 one tooth at a time.

At all times except when the barring stitches are being sewn, the pawl-carrying lever 211 is oscillated idly; the pawl 220 being held out of 60 engagement with the toothed sector 212 by means of the tail piece 236 which engages the holding pawl 237 on the lever 238 fulcrumed at 239 and having an arm 240 which engages under the clutch-operating lever 194, Fig. 4. The holding pawl lever 238 is biased by the spring 241 65 in a direction to carry the pawl 237 toward the toothed disk 212.

When the latch 199 is tripped by the lever 161, Fig. 37, to stop the feed and pattern wheels for 70 the barring operation, the up-motion of the clutch-operating lever 194 allows the holding pawl 237 and the actuating pawl 220 to both engage the toothed sector 212. Projecting downwardly from the hub of the toothed sector 212 75

is an arm 242 which is connected to the spring 243 anchored to the frame. This spring causes the lower end of the slot in the link 224, Fig. 11, to engage the screw-pin 225 on the push-bar 226 5 at all times except momentarily when the push-bar 226 is released by its hold-down latch 234 to throw in the rapid feed mechanism to be described, whereby the feed and pattern wheels are given a rapid motion both before and after the 10 sewing operation to carry the work-clamp rapidly up to and away from the stitch-forming mechanism. When the bar-stitch-counting mechanism is in operation, the toothed sector 212 is advanced one tooth at a time until the shoulder 244 thereon, Fig. 4, engages and trips the latch-lever 174 which releases the stop-motion lever 163 and allows the latter to move to stopping position. The stop 245, Fig. 4, is arranged to arrest the arm 242 when the reciprocating bar 226 is released 15 from its latch 234 for the rapid-feed throw-in operation.

The rapid-feed mechanism is of the conventional construction disclosed in the said Allen re-issued patent and in the Allen Patent No. 1,807,577, of May 26, 1931. The rapid-feed shaft 231 carries the worm 246, Fig. 1, which drives the gear 247 connected to the live element 248, Fig. 7, of a clutch on the cross-shaft 153. This clutch includes the cone element 249 which is actuated 20 by the clutch-operating arm 250 on the slide-rod 251. The slide-rod 251 is biased endwise by the spring 252, Fig. 7, in a direction to de-clutch the cross-shaft 153 from the rapid-feed shaft 231. The clutch arm 250, Fig. 7, carries a stud-pin 253 having two separate portions 253^a and 253^b, the portion 253^a of which, when the reciprocating clutch-operator bar 226, Fig. 11, is released by the latch 234, is engaged by the shoulder 254, Fig. 11, and pushed in a direction to withdraw the cone element 249 of the rapid-feed clutch and start the rapid-feed action. The slide-rod 251 is latched in its rapid-feed starting position by engagement of the notched plate 255, Fig. 10, of the latch-lever 256 with the tooth 257 of the plate 258 screwed to the clutch-shifter arm 250. The latch-lever 256 is fulcrumed on the stud-pin 259, Fig. 7, which is coaxial with the stud-pin 195, and is biased upwardly by the spring 260, Fig. 10. When the slide-rod 251 and clutch-shifter arm 250 are shifted to the left, Fig. 10, to start the rapid feed at the completion of the bar-stitching operation, the portion 253^b of the stud-pin 253 engages the inclined edge 261 of the lever 194 and depresses such lever into engagement with its latch 199, thus reclutching the feed and pattern-wheels with the main sewing shaft 5 for the next sewing period. The rapid-feed latch-lever 256 is connected as usual to the lever 262, Fig. 36, which is engaged by the usual rapid-feed throw-out tripping points 263, 264 on the pattern wheel. 50

The rapid-feed throw-in latch 234, Fig. 36, is actuated as usual by the arm 265 on the rock-shaft 266 which carries the arms 267 and 268, Fig. 1, arranged for engagement, respectively, by the usual 3-armed clamp-closing lever 269 and stop-motion actuated arm 270, such as disclosed in said Allen Patent No. 1,807,577.

The buttonhole-cutting mechanism is of the usual construction disclosed in said Allen re-issued patent and Allen Patent No. 1,807,577. The upper and lower cutter-levers 271, 272, Figs. 38 and 39, carrying, respectively, the punch 273 and apertured die 274, are fulcrumed at 275 on the cutter-carrier block 276 which is slidable in ways 70 277 in the bed 1 and is actuated by a link con-

nection 278 with the cutter-advancing and retracting cam 279 on the one-rotation cutter shaft 280 journaled transversely of the standard 2. The cutter shaft 280 also carries the cutter-closing cams 281, 282 which engage the rear ends 5 of the respective cutter-levers 271, 272 and spread them in the usual manner to close the cutter members 273 and 274.

The cutter-shaft is controlled by the usual single rotation clutch device comprising a driven disk 283, Fig. 1, carrying a radially movable clutch-tooth 284 on the slide 284^a which is held in retracted or disengaged position by the usual gate member 285 fulcrumed on the vertical stud-pin 286. When the gate 285, Fig. 8, is shifted inwardly to release the clutch-tooth-slide 284^a, the clutch-tooth 284 is engaged by a tooth 287 on the continuously running fly-wheel 288 and the cutter-shaft is driven through one complete revolution at the end of which the slide 284^a is re-engaged by the gate 285 and retracted to disengage the tooth 284 from the fly-wheel 288.

The three-armed clamp-closing lever 269 is actuated by the groove 289 of the fly-wheel 288 in the usual manner, as disclosed in the Spaine Patent No. 1,832,665, of Nov. 17, 1931, and need not be specifically described. It will suffice to explain that when the operator exerts a down-pull on the starting rod 290, Fig. 1, the slide-bolt 291 carried by the three-armed lever is released 30 by suitably timed mechanism and allowed to enter the cam-groove 289 which imparts one to-and-fro swinging impulse to the clamp-closing lever following which the slide-bolt 291 is ejected from the cam-groove 289 and latched in ejected position. In the down-motion of the forwardly extending arm of the clamp-closing lever 269, Fig. 1, such arm depresses the arm 292 on the connected rock-shaft sections 293 of the work-clamp and closes the clamp upon the work in a manner well known. 35

The needle-thread controlling mechanism comprises the take-up lever 294, Fig. 23, which is actuated by the crank 295 and anchored by the link 296 to the frame. The crank 295 is carried 45 by the vertical crank-shaft 297 which is connected by one-to-one bevel gears 298 to the upper shaft 10. The needle-thread *t* runs through two tension devices 299, 300. Both tensions are on during the sewing of the side stitches, so that the needle-thread *t* is caused to run straight along the top side of the work, Fig. 2, to make the usual pyramid purl stitch. 50

When the sewing has progressed to the point where the eyelet-end stitches begin, which is substantially at the point where the thin straight portion of the buttonhole slit terminates, the tension 300 is released by the action of the tension-release lever 301 fulcrumed at 302, Figs. 3 and 6, and having a lower end-portion which is 55 engaged and cammed outwardly from dotted line to full line position, Fig. 6, by the taper-nosed collar 302^a mounted on and adjustable lengthwise of the rod 302^b carried by and forming a rearward extension of the slide-rod 134 which travels longitudinally of the bed 1 with the work-clamp. When the sewing has progressed around the eyelet-end of the buttonhole, the taper-nosed collar 302^a travels rearwardly out of engagement with the tension-release lever 301 and the tension 300 is restored for the second straight side 60 stitching operation. 65

It has been found by experiment to be very desirable to sew the eyelet-end stitches under less needle-thread tension than the straight side 70 75

stitches, in order to avoid the pulling of the needle-thread inwardly around the eyelet-end to a final position too close to the slit-stitch needle-punctures. In other words, by reducing the 5 needle-thread tension in sewing around the eyelet-end of a pyramid-purl lock-stitch buttonhole, a finished buttonhole is produced with a minimum of distortion of the pyramid-purl in the region around the eyelet-end of the buttonhole.

10 When the end of the second side stitching operation is reached and the square-bar stitches 56, Fig. 2, are being sewn the tension 300 is again released by the action of the tension-release lever 301, the lower laterally bent end 303 of which 15 is engaged by the out-motion of the needle-vibration amplitude control lever 57.

When the sewing is completed, both tensions are released by the up-motion of the conventional stop-motion-controlled tension-release link 304, 20 such as disclosed in said Allen reissued patent. The link 304 is connected at its upper end to a bell-crank lever 305, 306 fulcrumed at 307 on the bracket-arm 3. The arm 306 has a forwardly curved cam-portion 308, Fig. 23, which is arranged to press inwardly against the tension-release lever 301 when the stop-motion device 25 operates to stop the stitch-forming mechanism. The bell-crank lever-arm 306 is also connected by the link 309 to the arm 310 of the tension-release 30 rock-shaft 311 which carries the tension-release arm 312 associated with the tension 299.

35 The machine is equipped with clamp-spreading mechanism and with clamp-opening mechanism, both of the usual construction disclosed in said Allen reissued patent. It is also equipped with the usual finger-starting lever 313 which actuates the lever 314 connected to the pull-rod 290.

Operation

40 The operator places the work in the open work-clamp 114, 130 and presses the starting button 313 which, through the lever 314, exerts a down-pull upon the starting rod 290 and initiates the action of the clamp-closing mechanism. The 45 three-armed lever 269, Fig. 1, receives one complete oscillatory impulse from the cam-groove 289, Fig. 8, in the fly-wheel 288. In the down-motion of the forwardly extending arm of such lever, the work-clamp is closed and in the recovery motion of such lever its depending arm depresses the arm 267 on the rock-shaft 266 and trips the latch 234, Fig. 36, to effect the coupling of the cross-shaft 153 to the rapid-feed shaft 231. The connected feed and pattern wheels 126, 50 152 are now rapidly driven to effect a rapid forward shift of the work-clamp from its initial retracted position to a position where the stitching is to begin.

55 When the work-clamp reaches sewing position, 60 the cam incline 113, Fig. 3, on the pattern wheel 152 engages the follower nose 172 on the lever 170 and shifts the stop-motion device to dotted-line or running position, in which position it is retained by the latch 174. At the same time the 65 tripping point 264, Fig. 36, acts upon the lever 262 to trip the latch-lever 256, Fig. 10, and effect the throw-out of the rapid feed.

70 The sewing now proceeds down the first side, around the eyelet-end and back along the return side of the buttonhole, during which sewing the feed and pattern-wheels are driven more slowly and in step-by-step fashion through the clutch-connection 179-181, Fig. 16, with the shafts 8 and 5 which drive the stitch-forming mechanism.

75 When the stitching along the return side of

the buttonhole reaches a point even with the initial stitches, the beveled nose 158 of the block 157, Fig. 37, on the pattern-wheel shifts the lever 147 to centralize the work-clamp relative to the vibrating needle 18 and, simultaneously therewith, 5 shifts the lever 161 to shift the lever 57 and increase the amplitude of vibration of the needle for the bar-stitching operation. The shift of the lever 57, Fig. 10, effects the tripping of the latch 199 and allows the clutch-lever 194 to 10 spring upwardly to disconnect the feed- and pattern-wheels from the main sewing shaft 5 so that they will stand still. Also, the up-motion of the clutch-lever 194 permits the spring-biased holding-pawl lever 240, Fig. 4, to rise and start 15 the bar-stitch counting mechanism.

When a given number of bar-strokes have been sewn, depending upon the setting of the bar-stitch indicator 215, the shoulder 244 of the toothed-sector 212, engages the latch 174 and 20 trips the stop-motion device, allowing the stop-motion lever 163 to spring back to its full line or stopping position, Fig. 3, to stop the stitch-forming mechanism.

The rising and falling of the stop-motion tooth 25 165 effected by its engagement with the notched stop-cam 166, Fig. 1, imparts an impulse to the rapid-feed trip-arm 270 which engages and shifts the arm 268 on the rapid-feed start-control shaft 266 to throw-in the rapid feed and effect the 30 rapid return of the work-clamp to its initial position in rear of the stitch-forming mechanism. In this action, the movement of the slide-rod 251, Fig. 10, to the left carries the stud 253^b 35 against the inclined edge 261 of the clutch-control lever 194 and depresses the latter to reconnect the feed- and pattern-wheels to the main-shaft 5 for the next buttonhole-producing cycle. The down-motion of the lever 194 also carries the arm 240 of the bar-stitch-counting 40 mechanism downwardly to the position shown in Fig. 4 and thus disengages the pawls 220 and 237 from the toothed sector 212 which springs back into engagement with its stop 214.

When the work-clamp reaches its initial or retracted position, the tripping point 315, Fig. 5, on the gear wheel 154 swings the lever 316 about its fulcrum 317 and shifts the cutter-shaft-control gate 285 inwardly to initiate the action of the cutter-shaft 280 which performs one complete rotation and effects the cutting of the buttonhole slit s, Fig. 2.

By providing for circular adjustment of the tripping points 173, 264 and 157 on the pattern-wheel 152, it is obvious that square-barred eyelet-end buttonholes of various lengths may be produced, or a set of interchangeable pattern-wheels 152 may be provided for this purpose. The buttonhole cutter levers should, of course, be provided with the punch and die elements of the proper length for the particular buttonhole being produced.

The needle-thread t, Fig. 23, runs from the supply to the tension 300, thence to the tension 299, thence around the guide-pin 318 and through 65 the check-spring 319 to the take-up 294. From the take-up 294 the thread leads forwardly through the stationary guide 320 adjacent the upper end of the hollow thread-conducting needle-bar 13, and thence down through the needle-bar and through the hole 321, Fig. 28, in the needle-clamp-block 28, to the needle 18.

The invention is not to be understood as limited to the details of construction and relative arrangements of parts shown and described as

various modifications may obviously be made by those skilled in the art within the spirit of the invention.

Having thus set forth the nature of the invention, what we claim herein is:—

1. A lock-stitch buttonhole sewing machine having, in combination, stitch-forming instrumentalities including an endwise reciprocatory and laterally vibratory needle, a loop-taker, and a bobbin within the field of action of said loop-taker, a work-holder, feeding means to relatively move the stitch-forming instrumentalities and work-holder to sew around a buttonhole, means to turn the stitch-forming instrumentalities about an axis normal to the plane of the work in sewing around one end of the buttonhole, and means to cut the buttonhole.

2. A lock-stitch buttonhole sewing machine having, in combination, stitch-forming instrumentalities including an endwise reciprocatory and laterally vibratory needle, a loop-taker, and a bobbin within the field of action of said loop-taker, a work-holder, feeding mechanism to relatively move the stitch-forming instrumentalities and work-holder to sew around a buttonhole, means to turn the stitch-forming instrumentalities about an axis normal to the plane of the work in sewing around one end of the buttonhole, means to stop the feeding mechanism and to control the stitch-forming instrumentalities to sew a predetermined number of barring stitches across the other end of the buttonhole, and means to cut the buttonhole.

3. A lock-stitch buttonhole sewing machine having, in combination, stitch-forming instrumentalities including an endwise reciprocatory and laterally vibratory needle, a loop-taker, and a bobbin within the field of action of said loop-taker, a work-holder, feeding mechanism to relatively move the stitch-forming instrumentalities and work-holder to sew around a buttonhole, means to turn the stitch-forming instrumentalities about an axis normal to the plane of the work in sewing around one end of the buttonhole, means to stop the feeding mechanism and control the stitch-forming instrumentalities to sew a predetermined number of barring stitches across the other end of the buttonhole, means to cut the buttonhole, and means acting subsequently to the sewing of the barring stitches to reversely turn the stitch-forming mechanism about said axis to restore it to its initial position.

4. A lock-stitch eyelet-end buttonhole sewing machine having, in combination, stitch-forming instrumentalities including an endwise reciprocatory and laterally vibratory needle, a loop-taker, and a bobbin within the field of action of said loop-taker, rotary supporting means for the stitch-forming instrumentalities, a work-clamp, means to relatively move the stitch-forming instrumentalities and work-clamp to sew around a buttonhole, said means including a longitudinal feed-cam, a lateral feed-cam, and a radial-stitch positioning cam to turn the stitch-forming instrumentalities about an axis normal to the plane of the work in sewing around one end of the buttonhole, means to drive said cams while the stitch-forming instrumentalities are operating to sew along the first side, around one end and back along the second side of the buttonhole, means to disconnect said cams from their driving means at the close of the second side stitching operation for a bar-stitching operation across the finishing end of the buttonhole; and means

to increase the amplitude of lateral vibration of the needle for the bar-stitching operation.

5. A lock-stitch eyelet-end buttonhole sewing machine having, in combination, a frame including a bed and an overhanging bracket-arm, 5 stitch-forming instrumentalities including a reciprocatory and laterally vibratory needle, a shuttle and a bobbin, rotary supporting means for the stitch-forming instrumentalities, a stop-motion device for the stitch-forming instrumentalities, buttonhole cutting mechanism arranged to cut the buttonhole with the work-clamp occupying a buttonhole-cutting position on said bed removed from sewing position, a feed-wheel and longitudinal feed connections for moving the 10 work-clamp from buttonhole-cutting position through sewing position in a direction lengthwise of said bed and the buttonhole to be stitched, means to start the stitch-forming instrumentalities when the work-clamp arrives at sewing position, means to turn the stitch-forming instrumentalities in sewing around the eyelet-end of the buttonhole, means to stop the feed-wheel for a square-bar-stitching operation when the work-clamp reaches a position in the second side 15 stitching operation on the buttonhole even with the initial stitch of the buttonhole, means to trip the stop-motion device to stop the stitch-forming instrumentalities when the square-barring operation is completed, and means to start 20 the feed-wheel to carry the work-clamp back to buttonhole-cutting position.

6. A buttonhole sewing machine having, in combination, a frame including a hollow bed, stitch-forming mechanism including an endwise 35 reciprocatory and laterally vibratory needle, a work-clamp, a feed-wheel in said bed and connections to move said work-clamp, a cross-shaft in said bed, geared one-to-one to said feed-wheel, a control wheel mounted on said cross-shaft externally of said bed, and means controlled by 40 said control wheel to increase the amplitude of lateral vibration of the needle in barring one end of the buttonhole.

7. A buttonhole sewing machine having, in combination, a frame including a hollow bed, stitch-forming mechanism including an endwise reciprocatory and laterally vibratory needle, a work-clamp, a feed-wheel in said bed and connections to move said work-clamp, a cross-shaft 50 in said bed geared one-to-one to said feed-wheel, a control wheel mounted on said cross-shaft externally of said bed, means controlled by said control wheel to increase the amplitude of lateral vibration of the needle in barring one end of the buttonhole, and means tripped into action by said control wheel to count the number of barring 55 stitches and bring the stitch-forming mechanism to rest after a predetermined number of barring stitches have been made.

8. A lock-stitch eyelet-end buttonhole sewing machine having, in combination, a frame including a bed and an overhanging bracket-arm, stitch-forming instrumentalities including a reciprocatory and laterally vibratory needle, a shuttle and a bobbin, rotary supporting means for the stitch-forming instrumentalities, a stop-motion device for the stitch-forming instrumentalities, buttonhole-cutting mechanism arranged to cut the buttonhole with the work-clamp occupying a buttonhole cutting position on said bed removed from sewing position, a feed-wheel and longitudinal feed connections for moving the work-clamp from buttonhole-cutting position through sewing position in a direction lengthwise 70 75.

of said bed and of the buttonhole to be stitched, a readily removable and replaceable control wheel connected to run with the feed-wheel and lateral feed connections for controlling the lateral position of the work-clamp in sewing the buttonhole, means on said control wheel to operate said stop-motion device to start the stitch-forming instrumentalities when the work-clamp arrives at sewing position, means to turn the stitch-forming instrumentalities in sewing around the eyelet end of a buttonhole, means on the control wheel to centralize the work-clamp relative to the field of lateral vibration of the needle for the bar-stitching operation when the second side stitching operation on the button-hole is completed, and means controlled by the control wheel to disconnect the feed and control wheels from their driving means during the bar-stitching operation.

9. A lock-stitch buttonhole sewing machine having, in combination, stitch-forming instrumentalities including an endwise reciprocatory and laterally vibratory needle, a loop-taker, and a bobbin within the field of action of said loop-taker, rotary supporting means for the stitch-forming instrumentalities, a sewing shaft connected to drive the stitch-forming instrumentalities, a stop-motion device for said sewing shaft, a feed-wheel connected to move said work-holder, a rapid-feed shaft and connections to rapidly drive said feed-wheel prior to sewing to rapidly shift the work-holder from buttonhole-cutting position to sewing position, means connected to the sewing shaft to more slowly drive the feed-wheel during the sewing of the first side, the first end and the return side of the button-hole, means connected to the feed-wheel to turn the supporting means for the stitch-forming instrumentalities about an axis normal to the work in sewing the first end of the buttonhole, means to disconnect the feed-wheel from the sewing shaft at the end of the return side-stitching operation for the bar-stitching operation across the second end of the buttonhole, means to trip the stop-motion device to stop the stitch-forming instrumentalities at the close of the bar-stitching operation, means to connect the rapid feed-shaft to the feed-wheel to shift the work-holder from sewing to buttonhole-cutting position and to reversely turn the supporting means for the stitch-forming instrumentalities to initial position, and means to cut the buttonhole.

10. A buttonhole sewing machine having a frame including a bed and an overhanging bracket-arm, a work-clamp including lower work-supporting plates and upper work-clamping feet mounted for movement over said bed, said work-supporting plates having a work-exposing slot therein, a reciprocatory and laterally vibratory needle above the work-clamp, a rotary turret below the work-clamp, an oscillatory shuttle and a bobbin carried by said turret, and a needle-throat-member carried by said turret and overhanging said shuttle, said needle-throat-member having a button-shaped portion disposed in said slot and adapted to engage the under surface of the work and support the work against the thrust of the needle.

11. A buttonhole sewing machine having a horizontally disposed work-clamp including lower work-supporting means and upper work-clamping feet, said lower work-supporting means having a work-exposing slot therein, a reciprocatory and laterally vibratory needle above the work-

clamp, a shuttle-race member below the work-clamp, rotary supporting means for the needle and shuttle-race member enabling them to be turned about a vertical axis to place the stitches radially around the eyelet-end of a buttonhole, an oscillatory shuttle carried by said shuttle-race member, and a needle-throat-member mounted on said shuttle-race member and having a raised button-like portion rising through the slot in said lower work-supporting means.

12. A buttonhole sewing machine having, in combination, a frame including a bed and bracket-arm, stitch-forming mechanism including an endwise reciprocatory hollow thread-conducting needle-bar, a laterally vibratory needle carried by said needle-bar, a shuttle and a bobbin, coaxial rotary supporting means in said bed and bracket-arm for the stitch-forming mechanism, a work-clamp, a crank-and-link needle-thread take-up mounted on top of the machine bracket-arm, a stationary thread-guide disposed adjacent the upper end of the needle-bar, and means to relatively move said stitch-forming mechanism and work-clamp to sew around a buttonhole.

13. In a buttonhole sewing machine, stitch-forming mechanism including a reciprocatory and laterally vibratory needle, a work-clamp, a feed-wheel connected to relatively move the stitch-forming mechanism and work-clamp, a main sewing shaft, a pin and star-wheel device driven by the sewing shaft, a throw-out stitching-feed-clutch-connection between said pin and star-wheel device and said feed-wheel, and variable amplitude needle-vibration means connected to be actuated by said pin and star-wheel device independently of said clutch-connection.

14. A lock-stitch pyramid-purl buttonhole sewing machine having, in combination, stitch-forming instrumentalities including an endwise reciprocatory and laterally vibratory needle, a loop-taker, and a bobbin within the field of action of said loop-taker, a work-clamp, feeding means to relatively move the stitch-forming instrumentalities and work-holder to sew around a buttonhole, needle-thread tensioning means, means to turn the stitch-forming instrumentalities about an axis normal to the plane of the work in sewing around one end of a buttonhole, automatic means to relieve the tension on the needle-thread in sewing around said end of the buttonhole, and means to cut the buttonhole.

15. A lock-stitch pyramid-purl buttonhole sewing machine having, in combination, stitch-forming instrumentalities including an endwise reciprocatory and laterally vibratory needle, a loop-taker, and a bobbin within the field of action of said loop-taker, a travelling work-clamp, feeding means to move the work-clamp in sewing around a buttonhole, needle-thread tensioning means, means to turn the stitch-forming instrumentalities about an axis normal to the plane of the work in sewing around the eyelet-end of a buttonhole, tension-release means actuated by the travelling movement of the work-clamp at the time the eyelet-end stitches are being sewn to relieve the tension on the needle-thread, and means to cut the buttonhole.

JOSEPHINE W. ALLEN.

Administratrix of the Estate of Edward B. Allen, 70
Deceased.

MAURICE D. KNOX.

HAROLD C. FAULKNER.
